Primary Examiner — Karen S Acker*Assistant Examiner* — Carmen Arellano-Lado(74) *Attorney, Agent, or Firm* — Gowling Lafleur Henderson LLP; Joseph Conneely(57) **CLAIM**

The ornamental design for a portable power supply, as shown and described.

DESCRIPTION

FIG. 1 is a front view of a portable power supply showing my new design;

FIG. 2 is a rear view thereof;

FIG. 3 is a right side view thereof;

FIG. 4 is a left side view thereof;

FIG. 5 is a top view thereof;

FIG. 6 is a bottom view thereof; and,

FIG. 7 is a front perspective view thereof.

The broken lines in the views depict features of the portable power supply that form no part of the claimed design.
